UNITED STATES PATENT OFFICE.

JOSEPH TUCK, OF JODIE, WEST VIRGINIA.

RAILROAD SWITCH.

Application filed March 16, 1926. Serial No. 95,070.

This invention relates to a novel railway switch, and has for one of its objects the provision of a simple, inexpensive and efficient structure of this character that may 5 be temporarily or permanently installed with comparatively little labor and expense.

With the foregoing and other objects in view the invention consists of the construction, combination and arrangement of parts 10 hereinafter fully described and claimed, and illustrated in the accompanying drawings, wherein:

Figure 1 is a top plan view illustrating a temporary installation of the switch,

15 Figure 2 is a sectional view taken on the vertical planes indicated by the line 2-2 of Figure 1,

Figure 3 is a sectional view taken on the vertical planes indicated by the line 3-3 of

20 Figure 1,

Figure 4 is a sectional view taken on the vertical planes indicated by the line 4-4 of Figure 1,

25 Figure 5 is a sectional view taken on the vertical planes indicated by the line 5-5 of Figure 1,

Figure 6 is a sectional view taken on the vertical planes indicated by the line 6-6 of Figure 1,

30 Figure 7 is a sectional view taken on the vertical plane indicated by the line 7-7 of Figure 1,

Figure 8 is a sectional view taken on the vertical plane indicated by the line 8-8 of Figure 1,

35 Figure 9 is a sectional view taken on the vertical plane indicated by the line 9-9 of Figure 1,

Figure 10 is a sectional view taken on the vertical plane indicated by the line 10-10 of Figure 1,

40 Figure 11 is a detail perspective view of the frog of the switch, and

45 Figure 12 is a detail perspective view of the frog of the switch looking at the same from another direction.

Corresponding and like parts are referred to in the following description, and designated in the several views of the accompanying drawings, by similar reference characters.

In the drawings, 1 and 2 designate the rails of a main track, and 3, 4 and 5 designate the rails of the switch. The switch 55 rail 3 is located between the main track rails 1 and 2, and the switch rails 4 and 5 are

located outside of the main track rails. A feathered switch piece 6 is pivoted as at 7 to the switch rail 3, and its free end is adapted when it is in closed position to abut against 60 the inner side of the main track rail 1. A bridge switch piece 8 is pivoted as at 9 to the switch rail 5, and is provided with a head flange 8^a, as most clearly shown in Figure 7, which is adapted to overlie the main track rail 2 when this switch piece is in closed position. The switch pieces 6 and 8 are connected together by a bar 10 through the medium of which they can be moved into closed or opened position and secured in 70 either one of such positions. The switch bar 10 is connected to the switch pieces, 75 and 8 by lugs 11 carried by the switch pieces, brackets 12 secured to the switch bar and provided with openings for the reception 75 of the lugs, and bolts 13 which pivotally connect the lugs to the brackets.

A frog 14, which is adapted to be mounted upon either of the main rails 1 and 2 so as to permit the switch to be arranged at either 80 side of the main track, is of elongated rectangular formation and provided in its under side with main track rail receiving grooves 15 and 16. The grooves 15 and 16 intersect and are arranged at an angle to the longitudinal median line of the frog 14. The groove 15 permits the frog 14 to be mounted upon the main track rail 2 when the switch is arranged as shown in Figure 1, and the groove 16 permits the frog to be 90 mounted upon the main track rail 1 when the switch is to be arranged at the opposite side of the main track. Due to the angular arrangement of the grooves 15 and 16 with respect to its longitudinal median line, the 95 frog 14 occupies an angular position with respect to the main track rail upon which it is mounted. The frog 14 is provided at its ends with dove-tail extensions 17 one of which contacts with the inner side and the other with the outer side of the web of the main track rail upon which the frog is mounted. To permit them to pass beneath and contact with the under sides of the head of the main track rail upon which the frog 100 is mounted, the extensions 17 are offset downwardly from the upper side of the frog. The frog 14 is secured in place by the extensions 17 and set screws 18 which latter have threaded engagement with the frog 105 and engage the web of the main track rail and webs of the switch rails 3 and 4.

In its upper side, the frog 14 is provided with wheel flange receiving grooves 19 and 20 which intersect and are arranged at an angle to the longitudinal median line of the frog. The groove 19 alines with the inner sides of the heads of the switch rails 3 and 4, and the groove 20 alines with the inner sides of the heads of the main track rails 2. The frog 14 is provided at its upper side and 10 in alinement with the grooves 19 and 20 with depressed seats 21, 22, 23 and 24 the purpose will presently appear.

The upper sides of the switch rails 3, 4 and 5 and main track rails 1 and 2 are located in the same horizontal plane, and the upper side of the frog 14 occupies a plane located above the rails. Bridge rails 25 and 26 overlie the main track rails 2 and are secured thereto and to the frog 14. A bridge rail 27 overlies the switch rail 3 and a bridge rail 28 overlies the switch rail 4, and are secured to these switch rails and to the frog 14. The bridge rails 25, 26, 27 and 28 incline upwardly in the direction of the frog 14, and are of similar formation in cross section, each having a head 29 overlying the main track rails and switch rails and having their adjacent ends positioned on the seats 21, 22, 23 and 24 of the frog 14. The adjacent ends of the heads 29 are provided with dowel pins 30 fitting in openings 31 in the seats of the frog 14. The bridge rails 25, 26, 27 and 28 also have vertical portions or webs 32 which contact with the sides of the heads of the main track and switch rails, and ribs or base flanges 33 which contact with the webs of the main track and switch rails. The bridge rails 25, 26, 27 and 28 are secured to the main track and switch rails and frog 14 by bolts 34. The bridge rails 25 and 26 carry the train over the frog 14 when the switch is opened, and the bridge switch piece 8 bridge rails 27 and 28, and frog 14, carry the train over the main track rail 2 when the switch is closed.

The temporary installation of the switch has been described and is illustrated in the drawings. When it is desired to effect a permanent installation of the switch, the bridge rails 25, 26, 27 and 28 are omitted and the frog 14 is inserted in one of the main track rails 1 and 2 in inverted position to present the grooves 15 and 16 uppermost for the reception of the wheel flanges of the train. To permit of this installation of the frog 14, one of the main track rails 1 and 2 is cut away for the reception of the frog and the frog is secured to the main track rail sections by the extensions 17 and bolts 18. In this installation of the switch, one of the grooves 15 and 16 will register with the inner sides of the heads of the switch rails 3 and 4 and the other with the inner side of the head of the main track rail to which the frog 14 is secured.

From the foregoing and accompanying drawings, it will be seen that the switch embodies a construction which will enable it to be installed at either side of the main track and which will enable it to be installed permanently or temporarily. The frog 14 may be readily and firmly secured upon one of the main track rails when it is desired to effect the temporary installation of the switch or within a cut out portion of one of the main track rails when it is desired to effect the permanent installation of the switch. The manner in which the bridge rails 25, 26, 27 and 28 are secured to the frog 14 and to the main track and switch rails prevents them from having any relative movement with respect to the parts to which they are secured. The frog 14 is held against vertical movement with respect to the main track rail and switch rails to which it is secured by means of its extensions 17 which in addition to contacting with the under sides of the heads of these rails also contact with the base flanges and webs thereof.

The ties 35 are especially adapted for supporting the switch rails and the main track rails at the point of installation of the switch. Each of these ties is provided adjacent its ends with upper recesses 36 for the reception of the rail bases and rail clamps 37. The tie 35 is provided with flanges 38 and the clamps 37 with flanges 39 which contact with the rail bases. The clamps 37 are provided with side portions 40 of reduced thickness which occupy horizontal grooves 41 formed in the tie 35 and communicating with the recesses 36. The vertical walls of the grooves 41 and the adjacent vertical edges of the clamp portions 40 are inclined transversely of the tie 35, and the clamp portions 40 are provided with slots 42 which are arranged in parallel relation to said inclined walls and edges. Bolts 43 pass through the tie 35 and slots 42 to secure the clamps 37 to the tie. The manner in which the clamps 37 are secured to the tie 35 is such that they move in the direction of the rails when driven transversely in one direction with respect to the tie and such that they move away from the rails when they are driven transversely in the opposite direction with respect to the tie. It will thus be seen that the rails can be readily and firmly secured to the tie 35 and readily released therefrom. The clamps 37 are held in rail retaining position by bolts 44 which pass through openings 45 in the clamps and openings 46 in the tie 35. To permit the clamps 37 to be swung free of the rails, the vertical walls of the grooves 41 have portions thereof inclined as shown at 47.

It should be understood that the drawings are merely illustrative and do not pretend

to give exact proportions. Furthermore, the said drawings are illustrative of a preferred construction, it being my expectation that various changes and modifications may 5 be made without departing from the spirit and scope of my invention.

What is claimed is:—

1. In combination, main track rails, switch rails, a feathered switch piece, a bridge 10 switch piece, a frog mounted upon one of the main track rails and secured thereto and to certain of the switch rails and having rail flange receiving grooves, bridge rails overlying said main track and switch rails, and 15 means securing the bridge rails to the frog and the rails which they overlie.

2. In combination, main track rails, switch rails, a feathered switch piece, a bridge switch piece, a frog mounted upon one of the 20 main track rails and secured thereto and to certain of the switch rails and having rail flange receiving grooves, bridge rails overlying said main track and switch rails, and means securing the bridge rails to the frog 25 and the rails which they overlie, each of said bridge rails having a head, a web and flange extending inwardly from the web.

3. In combination, main track rails, switch rails, a feathered switch piece, a bridge 30 switch piece, a frog mounted upon one of the main track rails and secured thereto and to certain of the switch rails and having rail flange receiving grooves, bridge rails overlying said main track and switch rails, and 35 means securing the bridge rails to the frog and the rails which they overlie, said frog having end extensions contacting with the

webs, heads and base flanges of said main track and switch rails.

4. A switch frog provided with rail flange 40 receiving grooves arranged at an angle to its longitudinal median line and provided at its ends with dove-tail rail engaging extensions.

5. A switch frog provided at its upper 45 side with angularly related wheel flange receiving grooves and at its other side with angularly related wheel flange and rail head receiving grooves, and said frog being provided at its ends with dove-tail portions 50 located between the grooves.

6. A switch frog provided at its upper side with rail flange receiving grooves and at its other side with rail flange and rail head receiving grooves, and at its ends with 55 dove-tail rail engaging extensions.

7. In combination, main track rails, switch rails, switch pieces, and a frog having wheel flange receiving grooves and provided with 60 dove-tail extensions adapted to contact with the bases, webs and heads of certain of the main track and switch rails.

8. In combination, main track rails, switch rails, switch pieces, bridge rails, and a frog 65 having wheel flange receiving grooves and provided at its ends with extensions against the opposite sides of which certain of the main track and switch rails are secured, said frog being also provided with depressed 70 seats for the reception of portions of said bridge rails.

In testimony whereof I affix my signature.

JOSEPH TUCK.
